UNITED STATES PATENT OFFICE.

JOHN WILLIAM SCOTT, OF BAYSIDE, NEW YORK, AND THOMAS HOAG GREER, OF BLOOMFIELD, NEW JERSEY.

SAFETY-TREAD.

1,338,332.

Specification of Letters Patent. Patented Apr. 27, 1920.

Application filed March 26, 1919. Serial No. 285,325.

To all whom it may concern:

Be it known that we, JOHN WILLIAM SCOTT and THOMAS H. GREER, citizens of the United States, residing, respectively, at 5 Bayside, Queens Co., N. Y., and Bloomfield, Essex county, New Jersey, have invented new and useful Improvements in Safety-Treads, of which the following is a specification.

- 10 This invention relates to safety tread structures for floors, stairs, inclined ways and the like and consists of an improved and novel arrangement and construction thereof, which is particularly adapted to facilitate the replacement and renewal of the safety treads when they become worn and to permit of this renewal with the minimum expense both as to material and the labor required therefor.
- 20 The objects and advantages of our present invention are more fully understood by comparison with the standard type of safety treads which heretofore had extensive commercial use particularly in connection with 25 subway and elevated railway operation. As is well known the factor of safety in connection with such installations is an important one, and it is the universal practice to employ non-slip tread surfaces particularly 30 upon stairs and where subjected to considerable wear it has been the common practice to employ various forms of separable non-slip or safety treads which are detachably secured to the stair treads or supports so as 35 to permit of their being replaced with new safety treads when they become worn to the danger point. These separable safety treads in the present standardized practice are formed of suitable non-slip material such 40 as steel having incorporated therewith lead or other non-slip material and are installed upon the stair treads in suitable lengths corresponding to the width of the stair and approximately the full width thereof so that 45 in the standard practice upon wearing out of the tread the unit to be replaced is of substantial length, as aforesaid corresponding to the full width of the stair treads. However, it is found in practice that in 50 many situations particularly in turns in stair ways and where a hand rail is present that the wear upon the safety tread is to a large degree localized with the result that the safety treads become worn through and 55 dangerous in one spot or on one side thereof

which necessitates the removal and replacing of the full width safety tread unit. Obviously this practice is accompanied by considerable waste of material which adds to the cost of maintenance.

The improved safety tread of the present invention is designed particularly with a view to avoiding the aforesaid waste incident to replacements and to that end consists of a safety tread construction embodying a plurality of safety tread blocks or insert units of reduced size and an improved arrangement for facilitating the removal and renewal of the smaller non-slip insert units. Accordingly, in the preferred embodiment of our invention there is employed a suitable supporting or safety tread frame adapted to have detachably secured thereto tread blocks or inserts of non-slip material and formed to provide the tread surface, 65 these blocks being of suitable size to permit of the removal and replacement of just that local tread surface which has become worn so as to reduce the waste to the very minimum and to effect a corresponding saving 70 in maintaining an effective non-slip tread surface. Further important features of our present invention reside in an improved construction and relative arrangement of the parts whereby the non-slip insert blocks 75 are securely and firmly supported in position in a manner whereby the individual blocks may be quickly and conveniently replaced and further in the improved form of block employed which is capable of being 80 positioned upon the frame so as to present a new surface thereof at the front or nosing portion of the safety tread at which point the greatest wear occurs. This latter improved feature is valuable and offers a further advantage in that the safety tread blocks may be shifted in position so as to obtain the greatest efficiency from the individual blocks and thereby further contribute to the economy effected.

The foregoing and other advantages of our improved tread will be understood by reference to the accompanying drawings wherein desirable embodiments of our invention are illustrated and wherein like 105 reference characters of this description are applied to corresponding parts in the several views.

Referring to the drawings Figure 1 is a plan view of a desirable construction of 110

safety tread embodying the features of the present invention. Fig. 2 is a view thereof partially in front elevation with portions thereof shown in vertical cross section. 5 Fig. 3 is a perspective view of a sectional portion thereof of the safety tread of Figs. 1 and 2. Fig. 4 is a similar view of an approved modified construction thereof. Fig. 10 5 is a perspective view of a desirably modified form of our invention particularly adapted for floors, inclined ways and the like. Fig. 6 is a partial perspective view of a further modification wherein our improved safety tread inserts are detachably 15 secured directly to a cast iron stair tread in the manner of our invention.

In Figs. 1, 2 and 3 we have shown an approved embodiment of the features of our invention in a detachable safety tread for stair ways which is adapted as a whole to be secured to the tread member of a stair by suitable screws or bolts. The safety tread as 20 shown comprises a supporting frame 1 of metal which may desirably be cast iron or steel in the form of a skeleton frame for the sake of lightness and economy of metal. This frame 1 is desirably composed of front and rear marginal members or bars 2 and 3 and side marginal members 4, 4 and intermediate 25 connecting members 5, 5 desirably equi-distantly spaced as shown and connecting the marginal members 1 and 2. The rear and side marginal members are desirably formed as shown with upturned vertical flanges 6 and the forward member 1 is formed with a depending vertical flange 7. The described arrangement provides 30 rectangular openings or sockets 8, 8 intermediate of the frame bars 5, 5 inclosed by the forward and rearward marginal frame 35 members 2 and 3. With relation to each of the sockets or openings 8, in the supporting frame, safety tread inserts or blocks of suitable non-slip material are provided and 40 adapted to provide the tread surface; these safety tread blocks 10 are here shown of rectangular form and supported at their marginal edges upon the frame bars inclosing the openings 8 and the tread blocks are 45 further provided on their under sides with a key portion enlargement 11 closely fitting the openings or sockets 8 of the frame. By 50 this arrangement upon positioning the tread blocks with the key portions fitted within the sockets the shoulders or ledges of the key portion by engaging the inner walls of the openings will effectually prevent lateral movement and displacement of the tread 55 inserts. 60 For the purpose of detachably securing the tread blocks in proper position upon the frame the side edged portions of the blocks may desirably be tapered or inclined as illustrated and to co-act therewith suitable key bars 13 are provided and adapted to be

secured to the frame and to clamp the tread blocks in position. These key bars 13 are formed with complementary inclined side portions 14 adapted to overlie the marginal sides or inclines of the tread blocks so as to 70 clamp the latter upon the frame when secured thereto. As shown the key bars are forwardly and rearwardly extended and are desirably of channel form throughout their length and are of corresponding height to 75 that of the tread blocks so that their upper surfaces are level therewith and said bars as shown are detachably secured in position by suitable screws 14, 14' fitting apertures 80 therein and threaded into the frame 1.

As will be obvious the key bars 13 when secured in position on the frame will operate to securely clamp the tread blocks upon the frame by engagement with the adjacent side portions of the blocks. This arrangement affords an effective means for securing 85 the blocks in position and one which permits of the individual blocks being readily and conveniently removed when desired by simply taking out the two securing screws 90 as shown. The channel form of key bars employed is desirable in that the channeling provides for drainage which is particularly desirable in some locations, lightens the metal employed, at the same time maintaining 95 a substantial depth thereof and further by the arrangement of the securing screws within said channels and suitable proportioning their length as here shown it results that the screws cannot loosen or be left in a position elevated above the tread surface. This latter feature is an important precaution 100 in avoiding the liability of tripping or catching of the foot upon securing screws which are not properly positioned.

A further important feature of the present invention consists in the proportioning and relative arrangement of the tread blocks with reference to the frame and in the improved form thereof which permits of these 110 tread blocks being reversible in position. To this end the tread blocks 10 are formed to correspond at both their forward and rearward portions as shown being formed with rounded off edge or nosing portions 15. The securing sockets 8, 8 and the key portion 11 of the tread blocks are so positioned relatively that they will properly determine the position of the rounded ends 15 of the tread block so that these rounded edges or nosings 120 15 will assume a corresponding position at the front edge of the frame upon the reversal of the block.

As will be readily appreciated the non-slip tread blocks or inserts 10 may be composed 125 of any suitable non-slip material or compositions such as a bonding material having an abrasive substance incorporated therein such as oxid of aluminum, carbide of silicon, flint, quartz or sand, the bonding mate- 130

rial may be of suitable cement or equivalent or these blocks may be made of lead or alloy which may have abrasive grains incorporated therein or they may be in the form of 5 tiles of vitreous material with suitable abrasive particles combined therewith. Or as will be further understood these non-slip 10 tread blocks may be formed of sections of any of the present types of non-slip treads and from the latter it follows that treads of the standard types when partially worn may be sawed into blocks of the form here shown and the good portions utilized in connection with my improved tread structure shown. 15 As illustrated the front and rear end portions of the key bars are of a form corresponding to the contour of the front and rear ends of the tread blocks. The key bars, as shown, extending to the forward edge of 20 the tread block offer protection to the latter in that they provide a bearing for the foot immediately adjacent the corners of the tread blocks at which point there is obviously the greatest danger of fracture. A 25 further advantage of the desirable form of key bar shown is that this key bar is also reversible in its position in similar manner to the blocks so that when the forward portion thereof becomes worn it may be reversed 30 in position to derive a renewed nosing portion.

While we have shown and described an approved form of our invention it will be understood that the same is subject to various 35 modifications without departing from the scope of the invention. For instance in Figs. 4, 5, and 6 we have shown suitable modified forms thereof embodying the features and advantages of our improved tread 40 as described in structures of differing form and arrangement.

In Fig. 4 a suitable modified safety tread is illustrated corresponding closely to the form of Fig. 1 but wherein the securing 45 means for the tread blocks is shown to consist of key members or clips 18 corresponding to sections of the described key bars 10. These clips are suitably secured in position by means of screws 19 passed therethrough 50 and threaded into the frame 1 corresponding to the method of securing the key bars 10 of the first described construction. The tread blocks as shown in corresponding manner are secured in position by the inclined 55 side walls of the clips 18 and intermediate of the clips the blocks are provided with abutting lateral extensions.

In Fig. 5 there is shown a desirable modified form particularly adapted for flooring 60 treads. As here disclosed it is designed that the tread blocks are of rectangular form and adapted to be secured to the floor by key bars of the form in cross section as described. As here shown the key bars may be 65 made up as an integral member having key

bar sections 21, 21 in crossed and right angular relation. As illustrated in this arrangement the securing screws for the key bars may be centrally arranged of the key members whereby the latter are securely positioned by means of a single securing screw 22.

In Fig. 6 we have shown a further desirable embodiment of our improved features incorporated in a cast iron stair tread structure. As here illustrated the stair tread member 24 is formed to generally correspond to the safety tread frame member 1 heretofore described, by having the upper surface thereof formed with a suitable depression 25 adapted to receive therein the tread blocks of our invention. This depressed portion of the stair tread is as shown formed with a series of socket depressions 26 adapted to coact with and receive therein the key portions 11 of our improved tread blocks. The detachable tread blocks or inserts as shown are secured in position by key bars 13 corresponding to the arrangement of the first described disclosure. This construction of Fig. 6 thus illustrates the manner in which the improved features of our invention may be embodied in a permanent stair tread structure or installation as distinguished from the separable safety tread 95 of Fig. 1.

We claim:

1. A safety tread comprising a metallic supporting frame adapted to be secured upon a stair tread, a plurality of tread blocks of non-slip material supported upon the frame with their side edge portions in close proximity and detachable key members interposed between the tread blocks and formed to overlie portions of the latter 100 to secure the blocks in position, said key members being arranged transversely to permit removal of any one of the tread blocks without disturbing the major area of the tread surface.

2. A safety tread comprising a metallic supporting frame adapted to be secured upon a stair tread, tread blocks of non-slip material supported in plural arrangement longitudinally on the frame with their side 110 edge portions in close proximity and detachable transverse key members interposed between the tread blocks and formed to overlie portions of the latter to secure the blocks in position, said key members being 115 arranged to permit removal of any one individual block without disturbing the remaining area of the tread surface and said tread blocks being formed to have retaining engagement with the frame to secure the 120 blocks from lateral displacement and provided with nosing portions at their forward and rearward edges and said frame and tread blocks being relatively formed to permit of the blocks being reversed to position 130

one or the other of the nosing portions at the forward edge of the frame.

3. A safety stair tread comprising a metallic supporting frame adapted to be secured upon a stair tread, tread blocks of non-slip material arranged in plural arrangement longitudinally of and supported upon the frame with their side edge portions in close proximity and detachable key members interposed between the tread blocks and extending transversely of the frame, said key members being formed to overlie portions of the tread blocks to secure the latter in position, said tread blocks having nosing portions extending to the forward portion of the frame and said key members having nosing portions co-extensive with the nosing portions of the tread blocks to protect the forward corners of the latter and said key members being longitudinally channeled to provide for drainage of the tread surface, substantially as described.

4. A safety tread comprising a metallic supporting frame adapted to be secured upon a stair tread structure, a plurality of tread blocks of non-slip material supported upon the frame member with their side edges in close proximity, said tread blocks being of substantially the full depth of the frame and having nosing edges formed thereon both at their forward and rearward edges, securing key bars interposed between the tread blocks and formed to overlie portions of the blocks to secure them in position, means detachable to secure the key bars to the frame, said key bars being arranged to extend transversely of the frame to permit removal of local areas of the tread

blocks without disturbance to the major area of the tread surface and to be co-extensive with the tread blocks to protect the forward corners of the latter and said key bars being formed with nosing portions at their forward and rearward edges to be reversible and having channels longitudinally formed therein for drainage of the tread surface, substantially as described.

5. A safety tread comprising a metallic supporting frame adapted to be secured upon a stair tread or supporting surface, said frame being of skeleton form having a series of openings or pockets arranged longitudinally thereof, tread blocks of non-slip material arranged to have bearing support upon the frame and provided with key portions fitting the frame openings and key members detachably secured to the frame and arranged to overlie portions of the blocks to secure the latter in position, said key members being arranged transversely of the frame to permit removal of individual blocks without disturbing the major portions of the tread surface and provided with longitudinal channels for drainage of the tread surface, said tread blocks being formed with nosing portions at their forward and rearward edges and the frame and blocks being relatively formed to permit of the blocks being reversed to position one or the other of the nosing portions at the forward edge of the frame, substantially as described.

In testimony whereof we have signed our names to this specification.

JOHN WILLIAM SCOTT.
THOMAS HOAG GREER.
